ELECTRIC LIGHTING FIXTURE

Oliver Lundquist, New York, N. Y., assignor to
Century Lighting, Inc., New York, N. Y., a cor-
poration of New York

Application January 22, 1949, Serial No. 385

Term of patent 14 years

(Cl. D48—23)

To all whom it may concern:

Be it known that I, Oliver Lundquist, a citizen of the United States, residing at the Borough of Manhattan, in the county of New York and State of New York, have invented a new, original, and ornamental Design for an Electric Lighting Fixture, of which the following is a specification, reference being had to the accompanying drawing, forming part thereof.

In the drawing:

Fig. 1 is a rear elevational view of an electric lighting fixture, showing my new design;

Fig. 2 is a side elevational view;

Fig. 3 is a top plan view;

Fig. 4 is a side elevational view, the shell hous-
ing being shown in a different position;

Fig. 5 is a front elevational view of Fig. 4; and

Fig. 6 is a bottom view of Fig. 4.

The broken lines shown in the drawing are for
illustrative purposes only.

I claim:

The ornamental design for an electric lighting
fixture, substantially as shown and described.

OLIVER LUNDQUIST.
